UNITED STATES PATENT OFFICE.

CHARLES A. LINDSTRÖM, OF PITTSBURGH, PENNSYLVANIA, ASSIGNEE TO PRESSED STEEL CAR COMPANY, OF PITTSBURGH, PENNSYLVANIA, A CORPORATION OF NEW JERSEY.

CAB-UNDERFRAME.

1,175,464.

Specification of Letters Patent. Patented Mar. 14, 1916.

Application filed January 17, 1914. Serial No. 612,613.

To all whom it may concern:

Be it known that I, CHARLES A. LINDSTRÖM, a citizen of the United States, residing at No. 138 Stratford avenue, Pittsburgh, 5 E. E., in the county of Allegheny and State of Pennsylvania, have invented certain new and useful Improvements in Car-Underframes, of which the following is a specification.

10 An object of the present invention is to provide a car underframe of light, economical and strong construction.

Another object of the invention is to provide a car underframe having the center and 15 draft sills formed and connected together in such a manner as to provide an opening for the passage therethrough of a bolster member.

A further object of the invention is to 20 provide an opening in the central longitudinal member of a car underframe to permit the passage therethrough of a portion of a bolster member without punching or slotted any of the constituent parts of said 25 central longitudinal member, *i. e.* the center and draft sills.

A specific object of the invention is to provide a car underframe having a portion of the adjacent ends of the center and draft 30 sills reduced in depth, preferably by removing a portion thereof or by any other suitable means, said end portions being arranged and connected together in such a manner that the end portion of one sill 35 takes the place of and compensates for the reduction in depth of the end portion of the other sill, and at the same time provide for an opening through the sills for the reception of a bolster member.

40 With these and other objects in view, the invention consists in the combination and arrangement of parts, as will hereinafter be more fully described, shown in the accompanying drawings, and particularly pointed out in the appended claims, it being understood that changes in the form, proportion, size and minor details may be made, within 45 the scope of the claims, without departing

from the spirit or sacrificing any of the advantages of the invention.

50 Referring now to the drawings in which like reference characters refer to like parts, and in which—

Figure 1 is a plan view of a portion of a car underframe embodying the invention; 55 Fig. 2 is a longitudinal section view on the line 2—2 of Fig. 1. Fig. 3 is an enlarged detail plan view of the bolster and a portion of the center and draft sills; Fig. 4 is a sectional view of the same on the line 4—4 of Fig. 1; Fig. 5 is a like view taken on the line 5—5 of Fig. 1. Fig. 6 is a sectional view on the line 6—6 of Fig. 1, and Figs. 7 and 8 are detail side elevational views of the draft and center sills respectively. 65

60 Referring now in detail to the drawings, 1, 1 indicate the center sills which are shown in the several figures of the drawings of substantially channel form in cross section, 70 each comprising a vertical web plate 2, having a flanged top or compression member 3, and a flanged bottom or tension member 4, secured thereto; but it will be understood that this invention is not limited to the specific construction of the center sills above 75 described, for it will be apparent to those skilled in the art that many other forms of spaced center sills may be used, and it will also be understood that what is known as a single center sill may be used. 80

In the specific embodiment of the invention as shown in the drawings, portions of the ends of the webs 2, 2 of the center sills are removed as at 5; the remaining end portions 6, 6 extending toward the end of the 85 underframe beyond the bolster 7 and being connected to the draft sills 8, 8 by rivets or other suitable means.

The draft sills 8, 8 are preferably of Z 90 form in cross section and at their outer ends are connected to the end sill 9 by any suitable means. Portions of the inner ends of these draft sills are removed as at 10, while the remaining end portions 11, 11 extend 95 toward the transverse centerline of the underframe, beyond the bolster 7, and are con-

nected to the center sills 1, 1. When the center sills 1, 1 and the draft sills 8, 8 are connected together, openings 12, 12 are formed which are adapted to receive the top member 13 of the bolster 7. The top member 13 extends preferably for the full length of the bolster and intermediate its ends, is provided with a center brace portion 14, which center brace portion is provided with flanges 15, 15 which are adapted to be secured to the center sills 1, 1.

To strengthen the underframe and to form an additional tie between the center and draft sills, a cover plate 16 may be provided which is secured to the top flanges of said sills and may extend for the full length or only a portion of the length of the underframe. These sills may be also strengthened and tied together by a plate 17 which is secured to the bottom flanges of said sills.

The bolster 7 is preferably an integral casting and, besides having a top member 13, has bottom members 18, 18 and webs 19, 19, which bottom members and webs stop short of the center sills 1, 1, and are connected together by a center bearing member 20. It will be seen that the top member 13, center brace portion 14, flanges 21, 21 and the center bearing member 20 form openings 22, 22, through which the end portions 6, 6 of the center sills pass. At each end this bolster is provided with flanges 23, 23 for the support of the side sills 24, 24, bracket 25, and the ordinary roping and jacking portion 26.

In building an underframe embodying the invention, the bolster 7 is positioned on the ends 6, 6 of the center sills 1, 1 and is connected thereto by any suitable means. The draft sills 8, 8 are then placed in such a position that they lap a portion of the ends 6, 6 of the center sills and when in such position are connected together by rivets or any other suitable means. When the draft sills are in position as just described it will be seen that the ends 11, 11 bridge the bolster 7 and are secured to the center sills, 1, 1.

In the drawings the ends 6, 6 of the center sill are shown passing through the bolster, and the ends 11, 11 of the draft sills passing over the bolster, but if desired the ends 11, 11 of the draft sills may be passed through the bolster, and the ends 6, 6 of the center sill may pass over the bolster.

The bolster 7 has been described as being of a single integral casting, but it will be understood that the invention is not limited to this type of bolster for it will be apparent that a bolster may be used which comprises a plurality of cast, pressed or rolled parts having a separate top member 13. This top member 13 may be continuous from side sill to side sill or may from a point in-

termidate the center and side sills at one side of the underframe to a corresponding point on the other side of the underframe.

Having thus described my invention, what I claim as new and desire to secure by Letters Patent is:—

1. The combination in a car underframe, of a central longitudinal member comprising a plurality of connected parts having portions of their adjacent ends reduced in depths, said parts being arranged in such a manner that the reduced end portion of one of said parts will compensate for the reduction in depth of the other of said parts and at the same time define an opening for the reception of a transverse member of the underframe.

2. The combination in a car underframe, of a center sill, a draft sill connected therewith and forming an extension thereof, said center sill and draft sills having their adjacent end portions reduced in depth and arranged in such a manner that the reduced end portion of one of said sills will compensate for the reduction in depth of the other of said sills, said end portions defining an opening for the reception of a transverse member of the underframe.

3. The combination in a car underframe, of a center sill having a portion of its end notched to effect a reduction in depth thereof; and a draft sill connected with said center sill and having a portion of its end notched to effect a reduction in the depth thereof, the end portions of said sills defining an opening.

4. The combination in a car underframe, of a central longitudinal member comprising a plurality of metallic parts connected together, said parts having portions of their adjacent ends removed to effect a reduction in the depth thereof, the remaining end portion of one part being adapted to take the place of the removed portion of the other part, said remaining portions of both of said parts defining an opening for the reception of a transverse member of the underframe.

5. The combination in a car underframe, of a flanged center sill, a flanged draft sill, said sills having portions of the ends of their webs and flanges removed, the remaining end portions being adapted to define an opening for the reception of a transverse member of the underframe when said sills are secured together.

6. The combination in a car underframe, of a center sill having a portion of its end notched to effect a reduction in the depth thereof, a bolster mounted on the remaining portion of said end, and draft sills having portions of their ends notched, the remaining portions of said draft sills pass-

- ing over said bolster and being secured to said center sill.
7. The combination in a car underframe, of center and draft sills having portions of their adjacent ends notched to effect a reduction in the depth thereof, a bolster mounted on the remaining portion of one sill, the remaining portion of the other sill being adapted to lap past and be secured to the first mentioned sill.
8. The combination in a car underframe, of a center sill, draft sills secured thereto, said sills having portions of their adjacent ends notched to effect a reduction in the depth thereof and to define an opening, a bolster member passing through said opening, and means for securing said bolster to said center sill.
9. The combination in a car underframe, of a central longitudinal member comprising a plurality of parts, all of said parts being connected together and having portions of their ends notched to effect a reduction in depth thereof, the remaining portions of said parts forming an opening, a bolster passing through said opening, and means for securing said bolster to one of said parts.
10. The combination in a car underframe of center sills of flanged form, having portions of their webs and flanges removed, draft sills of flanged form having portions of the ends of their webs and flanges removed, and means for connecting the remaining portions of said sills together, said remaining portions defining an opening.
11. The combination in a car underframe, of a bolster, center sills having portions of their ends notched to effect a reduction in the depth thereof, draft sills having portions of their ends notched to effect a reduction in the depth thereof, the remaining ends of said center sills passing through and connected to said bolster, and the remaining ends of said draft sills passing over said bolster, and means for securing said sills together.
12. The combination in a car underframe, of a bolster, center and draft sills having portions of their adjacent ends removed to effect a reduction in the depth thereof, said ends extending beyond said bolster and means for connecting said sills together on both sides of said bolster.
13. The combination in a car underframe, of a central longitudinal member comprising a plurality of parts, the upper end portion of one of said parts and the lower end portion of the other of said parts being notched, and means for securing said parts together, said end portions defining an opening for the reception of a transverse member of the underframe.
14. The combination in a car underframe, of a center sill having its end portion reduced in depth to form a notch, a bolster on said sill within said notch, and a draft sill overlapping said center sill and secured thereto.
15. The combination in a car underframe, of a center sill having its end portion reduced in depth to form a notch, a bolster on said sill within said notch, and a draft sill overlapping said center sill and secured thereto on each side of said bolster.
16. The combination in a car underframe, of a center sill having a notch in its end portion, a bolster mounted on said sill within said notch, and a draft sill secured to said center sill, said draft sill having its end portion reduced in depth and extending over said bolster.
17. The combination in a car underframe, of a bolster, a center sill having its end notched to effect a reduction in the depth thereof and extending through said bolster, a draft sill having its end notched and bridging said bolster, and means for securing said sills together.
18. The combination in a car underframe, of a bolster, a central longitudinal member comprising a plurality of parts, one of said parts passing through said bolster and the other of said parts lapping past said bolster the end portions of both of said parts being reduced in depth, and means for securing said parts together.
19. The combination in a car underframe, of a bolster, a central longitudinal member comprising a plurality of parts, one of said parts being reduced in depth at its end and passing through said bolster and the other of said parts bridging said bolster, and means for securing the said parts together.
20. The combination in a car underframe, of a bolster having a flange projecting therefrom, a center sill adapted to pass through said bolster and be connected with said flange, a draft sill overlapping said center sill on each side of said bolster, and means for securing said sills together, said sills being reduced in depth at the intersecting plane of the body bolster.
21. The combination in a car underframe, of a central longitudinal member comprising a plurality of parts having their adjacent ends reduced in depth, a bolster passing between said reduced ends, and means for securing said parts together.
22. The combination in a car underframe, of a central longitudinal member comprising a plurality of connected parts, said parts being reduced in depth at their ends, and a bolster mounted on one of said ends, the other of said ends bridging said bolster.
23. The combination in a car underframe, of a bolster, and a central longitudinal member comprising a plurality of connected

parts, said parts being reduced in depth at their ends, one of said reduced ends passing through said bolster and the other passing over said bolster.

5 24. The combination in a car underframe, of a sill comprising a plurality of connected parts, said parts being reduced in depth at their adjacent ends, and a bolster mounted between said ends.

10 25. The combination in a car underframe, of a bolster, a central longitudinal member

comprising connected draft and center sills, said sills having their adjacent ends reduced in depth and arranged to define an opening for the reception of said bolster.

In testimony whereof I affix my signature in presence of two witnesses.

CHARLES A. LINDSTRÖM.
